FIRE DOOR FRAME

George McCormick, Redwood City, and Ben M. Brown, Palo Alto, Calif.

Application October 11, 1943, Serial No. 505,890

2 Claims. (Cl. 122—499)

The present invention relates to frames for the fire doors of furnaces, and although particularly designed for the fire doors of locomotive boilers, is nevertheless adaptable to door installations of generally similar character.

The fire door opening of a boiler is subject to comparatively rapid deterioration of the steel walls, principally because of the frequent and violent changes in temperature caused by opening and closing the door and oxidation caused by large amounts of fresh air in contact with the heated walls.

It has been customary to form the fire door opening of locomotive boilers either by flanging the fire box wall or door sheet outwardly, joining it to the outwardly flanged outer shell or back head by welding or riveting, or by flanging the door sheet outwardly to about half the thickness of the water leg, flanging the back head inwardly to the same contour and welding the two flanges together. In either case, a separate fire door frame is customarily secured to the face of the back head by bolts, studs or rivets. In the first case, a filler ring is applied between the frame and the back head.

This construction has a number of disadvantages. The flanging of the back head and the door sheet to the exact contour required is difficult, particularly when renewals become necessary. The thickness of the sheets at points of maximum deterioration and stress is the same as over the remaining area, thus causing fractures and calling for repairs or replacement. Due to warpage, the joint between fire door frame and back head frequently becomes untight and causes air leaks.

The principal object of the present invention is to provide a fire door frame which completely displaces the back head and door sheet flanges, thus combining frame and flanges into a single unit. Another object is to provide a self reinforcing section, with maximum strength at points of greatest stress and exposure to deterioration. Other objects are to eliminate air leaks, to simplify installation and replacement, to reduce the amount and weight of steel, and to provide a door frame which will permit several removals and applications.

Still further objects and advantages of the invention will become apparent from the following description of a preferred embodiment, which should be read with the understanding that changes may be made in the form, construction and arrangement of the several parts herein illustrated and described, within the limits of the

claims hereto appended, without departing from the spirit of the invention.

Fig. 1 is a rear elevation of our improved fire door frame, with door removed.

Fig. 2 is a section on the line 2—2 of Fig. 1.

Figs. 3 to 6 inclusive are sections similar to Fig. 2 showing different ways of securing our fire door frame to the boiler sheets.

In the drawing, the reference numeral 7 designates the outer sheet or back head of a locomotive boiler, and 8 is the inner shell or fire box wall. To avoid confusion hereinafter, the outer sheet 7 will be termed the rear sheet, and the inner sheet 8 will be termed the front sheet, the terms 10 rear and front designating the actual positions of the sheets in the locomotive. Our improved fire door frame 9 comprises a ring like structure, preferably a steel casting, having whatever contour may be desired for the door opening, in this 15 case elliptical, and having a uniform cross section primarily of T shape. The leg 10 of the T is a flange extending outwardly all around the frame, and is secured to the outer or rear boiler sheet 7 preferably by welding. This joint between the 20 flange 10 and the rear sheet 7 may be butt welded, as shown at 11 in Figs. 2 to 5, or it may be lap welded, as shown at 12 in Fig. 6. One arm 13 of the T extends rearwardly at right angles to the leg flange 10, and forms a flange against 25 which the movable door (not shown) seats. The other arm 14 of the T extends forwardly at right angles to the leg flange 10 and in line with the arm flange 13, and is welded to the fire box wall 30 or front boiler sheet 8 as shown at 15. The arm flanges 13 and 14 thus form the boundary wall of the fire door opening, and the leg flange 10 forms the face plate of the frame, from which extend integral hinge lugs 16 and latch lugs or lock stops 17 for the movable door.

Our improved door frame can be used either in new construction or as a replacement part for old boilers, and by extending the leg flange 10 and the inner arm flange 14 more or less, it can be mounted in boilers of varying construction or condition. Thus for example the inner flange 14 can be bent outwardly, as shown at 18 in Fig. 2, parallel with the flange 10. In this example, 40 which may well be an old boiler showing considerable deterioration around the fire door, the sheets 7 and 8 of the boiler have been cut back considerably and to equal distances from the center of the opening, and the flanges 10 and 18 of our door frame are extended sufficiently to 45 be butt welded to the cut back sheets at 11 and 50 55

15. Stay bolt holes 19 are formed in both flanges of the frame in this case.

In the example shown in Fig. 4, the boiler sheets 7 and 8 have been cut back less than in Fig. 2. The flanges 10 and 18 of the frame are therefore shorter, and the stay bolt holes 19 are formed in the boiler sheets instead of in the frame flanges. The construction shown in Fig. 4 may well be followed in mounting our frame in new boilers.

Fig. 5 shows an example in which the rear sheet 7 of the boiler has been cut back more than the front sheet 8. The frame flange 10 is therefore wider than the flange 18. The outer stay bolt hole is in the frame flange 10 and the inner stay bolt is in the boiler sheet 8.

Fig. 3 shows an example of either a new boiler or one in which little deterioration has occurred, where the front sheet 8 has been flanged outwardly at 20 and is still in good condition. Our frame in this example has its simplest basic T section, the arm flange 14 being straight and butt welded at 15 to the outwardly flanged front sheet 8. Both stay bolt holes are in the boiler sheets.

Fig. 6 shows an example in which the front sheet 8 has been cut back farther than the rear sheet 7. The leg flange 10 of the frame in this case may be lap welded to the sheet 7 at 12, and the stay bolt holes are formed as shown. The flange 10, obviously, may be inside the rear boiler sheet 7, instead of outside as shown, and may be secured thereto by bolts or rivets instead of by welding.

It will be apparent from the foregoing that our improved fire door frame provides a simple easily formed structure that can be applied at minimum cost in time and labor either to new boilers or as a replacement in old boilers needing repair. Moreover, because of its one piece construction, and its basic T sectional shape, it provides maximum strength and minimum weight. It has no double walled portions exposed to extreme temperature

changes, and therefore is less subject to warping and cracking than the usual construction. It requires no filler ring or no extra ring around the opening, and the door can be set quite close to the head of the boiler, thus saving space.

We claim:

1. Fire door construction for a locomotive boiler having a front sheet and a rear sheet spaced to form a water leg, comprising an integral ring like door frame of substantially T shaped uniform cross section having an outwardly extending flange aligned with the rear boiler sheet and butt welded thereto, a second flange extending forwardly approximately at right angles to the first mentioned flange, said second flange being butt welded to the front boiler sheet, and a third flange extending rearwardly in substantial alignment with the second flange, the rear edge of said third flange forming a continuous seat for a door.
2. Fire door construction for a locomotive boiler having apertured front and rear sheets spaced to form a water leg, comprising an integral ring like door frame of substantially T shaped cross section uniform throughout its circumference, said frame having an outwardly extending flange, a second flange extending forwardly approximately at right angles to the first mentioned flange, the outer edge portion of said flanges being formed to adjoin the edge portions respectively of the rear and front boiler sheets, the edge portion of at least one of said flanges being aligned with and butt welded to the edge portion of the corresponding boiler sheet and the other flange being permanently secured to the other boiler sheet, and a third flange extending rearwardly in substantial alignment with the second flange, said third flange being continuous throughout the circumference of the frame and having a rear edge which forms a continuous seat for a door.

GEORGE McCORMICK,
BEN M. BROWN.
